UNITED STATES PATENT OFFICE.

WILLIAM H. REYNOLDS, OF DE SOTO, MISSOURI.

COLLAR-FASTENER.

1,301,745.

Specification of Letters Patent. Patented Apr. 22, 1919.

Application filed August 28, 1918. Serial No. 251,810.

To all whom it may concern:

Be it known that I, WILLIAM H. REYNOLDS, a citizen of the United States, residing at De Soto, in the county of Jefferson 5 and State of Missouri, have invented new and useful Improvements in Collar-Fasteners, of which the following is a specification.

This invention relates to new and useful improvements in collar buttons and the 10 principal object of the invention is to provide a device for use at the rear of the shirt band.

Another object of the invention is to provide a device of this character which is 15 simple and durable in construction, reliable and efficient in operation and one which can be manufactured and placed upon the market at a minimum cost.

The invention also consists in certain 20 other features of construction and in the combination and arrangement of the several parts, to be hereinafter fully described, illustrated in the accompanying drawings and specifically pointed out in the appended 25 claim.

In describing my invention in detail, reference will be had to the accompanying 30 drawings wherein like characters denote like or corresponding parts throughout the several views, and in which:—

Figure 1 is a front view of the device.

Fig. 2 is a view of the device in place in a shirt.

Fig. 3 is a section on line 3—3 of Fig. 2.

Fig. 4 is a front view showing a modification.

In these drawings 1 represents the body 40 of the device, which is preferably made of wire bent into the form shown in the drawings. The body comprises a pair of tongues 2, spaced apart and located on each side of said body. One end of the wire after leaving the last tongue is bent at right angles and extends centrally between the said 45 tongues, as shown at 3. Midway the body a head 4 is formed by forming a loop in the wire as it passes from one side of the body to the other. The end 3 extends into

the loop of this head, as clearly shown in the drawing. Near the extreme end of this 50 part 3 a kink 5 is formed and the tip end of the head or loop 4 is slightly raised as at 6. In using the device the body part is placed within the pocket 7 formed at the rear part of the shirt band 8 with the head 55 passing outwardly through the button hole and the part or finger 3 passing along the inner face of the band below the button hole, as clearly shown in Fig. 3. In this way part of the shirt band is grasped between 60 the head and finger and when the head is placed through the button hole in the collar said collar will also be grasped between these parts. In this manner the collar will be prevented from rising at the rear of the 65 neck.

In the modification shown in Fig. 4 the body is made plain as the tongues shown in the other figures are omitted. This form of the invention is provided with the head 4' 70 and the finger 3' before "described."

It is thought from the foregoing description that the advantages and novel features of my invention will be readily apparent.

I desire it to be understood that I may 75 make changes in the construction and in the combination and arrangement of the several parts, provided that such changes fall within the scope of the appended claim.

What I claim is:—

A collar button formed of wire comprising a body part, a head part formed by an extension loop located midway the ends of the body part, the extreme end of said head being slightly raised and a spring finger 85 connected with the upper side of the body part and extending through same into the loop of the head part, said finger having a kink at its end and terminating an appreciable distance from the inner curve of the 90 end of the head part so that the collar and shirt band are gripped by the two parts of the head part and said finger.

In testimony whereof I affix my signature.

WILLIAM H. REYNOLDS.
